WELDING TORCH

Milo M. Kensrue, 13882 Sanderstead Road,
Santa Ana, Calif. 92705

Filed Oct. 10, 1966, Ser. No. 4,219

Term of patent 14 years

(Cl. D62—2)

FIG. 1.

FIG. 3.

FIG. 2.

FIG. 4.

FIG. 5.

FIG. 6.

FIG. 7.

FIG. 1 is a perspective view of a welding torch showing my new design;

FIG. 2 is an elevational view of the left end of the view as seen in FIG. 1;

FIG. 3 is an elevational view of the opposite end;

FIG. 4 is an elevational view of the visible side as seen in FIG. 1;

FIG. 5 is an elevational view of the opposite side;

FIG. 6 is a top plan view; and

FIG. 7 is a bottom view of the same.

The dominant features of my design reside in the portions shown in full lines.

I claim:

The ornamental design for a welding torch, as shown and described.
